Primary Examiner — Cynthia Ramirez*(74) Attorney, Agent, or Firm* — Edwards Wildman Palmer LLP; Steven M. Jensen; Richard B. Emmons**CLAIM**

The ornamental design for a resealable container, as shown and described.

DESCRIPTION

FIG. 1 is a perspective view of the top, back, and right side of a container showing an embodiment of the new design;

FIG. 2 is a front view thereof;

FIG. 3 is a back view thereof;

FIG. 4 is a left view thereof;

FIG. 5 is a right view thereof;

FIG. 6 is a top view thereof; and,

FIG. 7 is a bottom view thereof.

The container is shown with a symbolic break in its length. The appearance of any portion of the article between the break lines forms no part of the claimed design.
